UNITED STATES PATENT OFFICE.

WILLIAM S. LANGFORD, OF BALTIMORE, MARYLAND.

BELTING.

Application filed October 21, 1922. Serial No. 595,937.

To all whom it may concern:

Be it known that I, WILLIAM S. LANGFORD, a citizen of the United States, and a resident of Baltimore, in the State of Maryland, 5 have invented certain new and useful Improvements in Belting, of which the following is a specification.

This invention relates to improvements in belting and has for its object the provision 10 of stitched belting which will not stretch, unravel, or pull out of the lace holes when spliced, or break, which usually occurs due to a regularity of stitching.

A further object of the invention is the 15 provision of a reinforced stitching for belting in which the length of the stitches in adjacent rows are variable and in which the stitches of each row in the belting are located in staggered relation so that at no 20 time are the entering points of the stitches of the several rows arranged in a line running transversely of the belt but are in staggered relation.

Another object of the invention is the 25 provision of a plurality of lines of longitudinal stitching for a solid woven belt, with the stitches of the various lines located in staggered relation whereby the tendency to transverse breakage of the belt is decreased.

30 Other objects and advantages of the invention will be apparent during the course of the following description.

The invention is illustrated by way of example in the accompanying drawings, in 35 which,

Figure 1 is a plan view of a section of the belting showing the preferred form of stitches located in staggered relation.

Figure 2 is another form of stitching 40 forming part of my invention.

Figure 3 is still another form of the stitching according to my invention for reinforcing belting.

Figure 4 is a transverse section of the 45 belting shown in Figure 3.

Belting usually employed for commercial purposes may be of three standard types, such as,

(1). Rubber belting constructed from 50 single layers of canvas or duck, treated with rubber, then laminated or folded to the required thickness and in some instances stitched and then put under pressure and vulcanized.

55 (2). Stitched canvas belting constructed

from cotton duck or other fabrics woven to the required width or thickness and then folded or laminated so as to form two or more plies, then stitched longitudinally or obliquely, with each stitch being of the same 60 length. The stitched canvas belting is then impregnated with oils or gums, stretched and then painted.

(3). Solid woven belting which is constructed from spun or twisted yarn such as 65 cotton jute and camel's hair, woven into solid form, the strands or layers of yarn amalgamating with one another until the required thickness is obtained.

Solid woven belting as is well known is 70 only adapted for very light work since it stretches very readily when put under strain, unravels and pulls out at the lace holes when spliced.

The first two forms of belting have been 75 stitched for locking the plies together but as far as I am aware no form of stitching has been employed on solid woven belting and it is to this form of belting that my 80 form of improved stitching is adapted to be applied. Such stitching increases the life of the belting by preventing stretching, unravelling and tearing out of the lace holes and likewise prevents transverse breaking of the belting due to the irregularity 85 of the positions of the various stitches forming each line of stitching.

Referring to the drawings, 1 designates a solid woven belt which is provided with a line 2 of stitching with the stitches each $\frac{5}{16}$ 90 of an inch long and an alternating line of stitching 3 with each stitch in said line approximately $\frac{7}{16}$ of an inch long. The lines of stitches are substantially placed $\frac{1}{4}$ of an 95 inch apart.

It will be noted in this form of stitching that none of the points 4, 5, 6, 7, and 8 through which the stitches are passed are in transverse alinement but are located in staggered relation with each other. An object of this form of stitching is to prevent 100 weakening of the belting along transverse lines of the belting. Figure 1 discloses the preferred form of my invention.

A second form of my invention is disclosed in Figure 2 in which stitches 9 are longer than stitches 10. It will be seen that 105 stitches 9 and 10 of each row are alternately disposed so that the points 11, 12, 13, 14 and 15 are located out of transverse aline- 110

ment so that the belting will not be weakened by a series of perforations extending transversely of the belt and in the same line.

6 The small stitch of one row of stitching, shown in Figure 2, is located opposite the larger stitch in an adjacent row.

10 In Figure 3 is shown another form of my invention in which the stitches 16 of one row are substantially of the same length, while the stitches of an adjacent row are alternately long and short. It will be seen that in this form, as well as in the other two forms, the stitches of the various rows are always located in staggered relation.

15 The length and position of the stitches gives the staggered relation of the perforations 18, 19, 20, 21 and 22 of Figure 3. The staggering of these perforations will prevent breakage of the belt on a line which

20 runs directly transversely of said belt.

Were the perforations through which ends of the stitches pass all located in transverse lines at right angles to the running length of the belt, the stitches would cause 25 a weakening of the belt along these lines and the belting would readily break at these portions. By staggering the stitches and likewise the penetrating points of the stitches, the direct lines of breaking will 30 be dissipated with the effect of greatly increasing the life of a belting.

What I claim is:

1. A solid woven belting provided with a plurality of lines of stitching disposed longitudinally of the belting, the stitches of the several lines of stitching being of varying lengths, said stitches interlocking with the woven elements of the belting and forming with the belting a unitary structure.

2. A solid woven belting provided with a plurality of lines of stitching disposed longitudinally of the belt, the stitches of one row being equal in length, while the stitches of alternating rows are equal in length but longer than the stitches of the first mentioned row, said stitches interlocking with the woven elements of the belting and forming with the belting a unitary structure.

3. A solid woven belting provided with a plurality of lines of stitching disposed longitudinally of the belting, the stitches of the several lines of the stitching being of varying lengths with certain of the stitches in one row being longer than the 55 stitches in an adjacent row with the stitches of one row located in staggered relation with the stitches of an adjacent row, said stitches interlocking with the woven elements of the belting and forming with the belting a 60 unitary structure.

WILLIAM S. LANGFORD.
